US0D1078685S

(12) **United States Design Patent** (10) **Patent No.:** **US D1,078,685 S**
(45) **Date of Patent:** **** Jun. 10, 2025**

(54) **LOUDSPEAKER**

(71) Applicant: **Harman International Industries, Incorporated**, Northridge, CA (US)

(72) Inventors: **Alexander Demin**, Shenzhen (CN); **Tao Lu**, Shenzhen (CN); **George Georgallis**, Northridge, CA (US); **Jacques Spillmann**, Los Angeles, CA (US)

(73) Assignee: **Harman International Industries, Incorporated**, Northridge, CA (US)

(**) Term: **15 Years**

(21) Appl. No.: **29/942,651**

(22) Filed: **May 16, 2024**

Related U.S. Application Data

(63) Continuation of application No. 29/812,624, filed on Oct. 22, 2021, now Pat. No. Des. 1,032,558.

(57) **CLAIM**

The ornamental design for a loudspeaker, as shown and described.

DESCRIPTION

FIG. 1 is a top, front perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines immediately adjacent the shaded areas represent the bounds of the claimed design, while all other broken lines are portions of the loudspeaker that form no part of the claimed design.

1 Claim, 7 Drawing Sheets
